UNITED STATES PATENT OFFICE

2,504,555

FLUSH VALVE

Raymond H. Loether, Pittsburgh, Pa.

Application February 26, 1948, Serial No. 11,172

4 Claims. (Cl. 4—56)

1

This invention relates to new and useful improvements in flush valves for water closets and it is among the objects thereof to provide a flush valve structure that is self-aligning and centers with the tank outlet when the valve is released.

It is a further object of the invention to provide a flush valve construction employing a center plumb-bob or weight which is movable relative to the rubber ball valve without interfering with the floating action of the latter to permit complete escapement of the water flowing from the tank.

These and other objects of the invention will become more apparent from a consideration of the accompanying drawings constituting a part hereof, in which like reference characters designate like parts, and in which

Fig. 1 is a vertical cross-sectional view taken longitudinally of a water closet flush tank embodying the principles of this invention;

Fig. 2 a similar view partially in elevation showing the flush valve in an unseated position;

Fig. 3 a view as in Fig. 2 illustrating the position of the valve with a reduced water level in the tank;

Fig. 4 an enlarged detail of the improved flush valve and plumb-bob embodying the principles of this invention; and

Fig. 5 a top plan view of the flush valve taken along the line 5—5, Fig. 4.

In the drawing numeral 1 designates a water closet tank having a water inlet connection 2 and an outlet connection 3, the latter communicating with the toilet. Numeral 4 designates the valve line leading to a valve 5 controlled through a system of levers 6 by the float ball 7. Numeral 8 designates the water inlet pipe to the tank and the numeral 9 designates the overflow pipe which determines the level of the water at the top 10 thereof. Mounted on the overflow pipe is a bracket 11 for guiding a valve rod 12 which is provided with the usual eye 13 and interacts with a link 14 of an actuating lever 15 that is manipulated by the handle 16, Fig. 2, in the conventional manner to lift the rubber valve 17 from its seat 18 at the outlet 3 of the tank. The tank construction, the inlet water control valve, overflow pipe and operating levers may be of standard construction and constitute no part of the present invention.

The invention deals with the construction of the flush valve 17 which, as is more clearly shown in Fig. 2, is open at the bottom at 19 whereas in the conventional form the valve rod 12 is fastened

to the rubber valve 17 by a threaded connection in the throat or neck 20 of the valve.

In accordance with the present invention the valve rod 12 is not fixed to the valve 17 but extends through an opening 21 of the neck 20 to provide sliding movement of the valve 17 on the rod 12. The end of the rod is provided with a plumb-bob 22 which, as is more clearly shown in Fig. 4, is secured to the rod 12 by a threaded connection at 23. The member 22 is cast metal and is provided with a recess 24 in which additional weight, such as washers, can be placed if desired. The plumb-bob 22 is of conical shape and centers itself in the valve 17 at the opening 19. As shown in Fig. 4, the rubber valve 17 is provided with a ferrule 25 having an opening 26 of sufficient clearance to permit free sliding movement of valve 17 on the valve rod 12.

The function of the weighted valve rod or plumb-bob 22 is as follows. As shown in Fig. 1, the flush valve 17 is in seated position, in which position the plumb-bob 22 rests in the opening 19, being centered therewith when the handle 16 of the flush valve is released. As shown in Fig. 2, the handle 16 has been tripped, raising lever 15 and its connected link 14 which lifts the valve rod 12 until the plumb-bob 22 engages the underside of the valve, and further movement of the lever 15 will unseat the valve 17 as shown. The water of the tank then escapes through the outlet 3 into the toilet bowl with the valve 17 gradually dropping with the level of the water in the tank as shown in Fig. 3. Handle 16 is in the released position as shown in Fig. 3, in which position the lever 15 has dropped but the valve rod 12 is retained in the raised position of Fig. 2 by virtue of the rubber flush valve 17 floating at the level of the water. The plumb-bob 22 has dropped a short distance to seat in the opening 19 of the flush valve and because of the clearance of the opening 21 with the valve rod 12, the flush valve 17 is centered by engagement of the plumb-bob 22 with the bottom opening 19. As the water level drops to the point where the flush valve 17 no longer floats, it will drop to the seating position of Fig. 1, the weight of the plumb-bob centering the flush valve 17 on the seat 18. The flush valve is thus set for the next flushing operation.

It is found by the use of the relatively movable flush valve 17 and plumb-bob 22 that the latter will center the flush valve on the seat 18 and also align it properly before engaging the seat 18.

Without the use of the plumb-bob 22 and with the flush valve 17 fastened to the valve rod 12 in

the conventional type of flush valve construction, the valve becomes misaligned with the seat 18 and will not always seat on the same face. This results in wear of the valve and leaking of the passage that is so annoying in the operation of flush tanks. It is found that by the use of the plumb-bob and the sliding action of the flush valve on the valve rod 12, this difficulty is entirely eliminated because the valve is at all times maintained in proper alignment and centered when lowered on its seat.

Although one embodiment of the invention has been illustrated and described it will be evident to those skilled in the art that various modifications may be made in the details of construction without departing from the principles herein set forth.

I claim:

1. A flush valve for water closets comprising a rod adapted for sliding movement in a guide bracket, said rod having a weight at its lower end to maintain the same in vertical alignment, a flush valve of resilient material slidably mounted on said rod having an opening at the bottom thereof of a dimension less than the cross sectional area of the valve rod weight, the said weight being disposed inside of the flush valve for engaging the upper wall of the valve when the valve rod is raised and for seating on the bottom valve opening when the valve rod is lowered.

2. A flush valve comprising in combination a hollow rubber bulb-shaped body having a valve rod slidably mounted therein and having a bottom opening, said valve rod extending through the upper wall of the bulb and being freely slideable therein, and a weight secured to the end of the rod inside of the bulb, said weight being of a cross sectional area greater than the bottom opening of the bulb and being adapted to seat in said opening to pilot the bulb in its lowering movement.

3. In a water closet flush tank having an overflow opening at the bottom thereof, a flush valve controlling the flow of water through said opening, said valve comprising a hollow rubber bulb-shaped member having an opening at the bottom

5
10

thereof, a valve rod mounted in said tank extending through an opening of the flush valve and having a weight secured at the lower end thereof, said rod being adapted to be actuated to raise said valve, and said weight being disposed inside of said bulb and being of a size to rest upon the bottom opening of the valve, the valve being freely slideable on said rod whereby upon lifting of the valve rod the weight will engage the valve and raise it from its seat, and upon the release of the valve rod the said weight will fall to a resting position in the bottom opening of the valve to pilot the valve in its downward movement.

4. In a flush valve for water closets, a valve rod suspended in a water tank and being connected to be actuated by movement in an axial direction vertically in said tank, the said rod having a cone-shaped weight in the lower end thereof, a flush valve comprising a hollow bulb-shaped rubber member slidably mounted on the valve rod and having a bottom opening of a dimension less than the diameter of the conical weight whereby upon lifting of the valve rod the weight engages the upper wall of the valve to unseat the same and when released the weight drops and engages the opening in the lower wall of the valve to bring the seat of the valve in alignment with the seat of an outlet in said tank.
